ELECTRONIC TUBE STRUCTURE

Charles L. Taylor, Owensboro, Ky., assignor to General Electric Company, a corporation of New York

Application September 13, 1954, Serial No. 455,531

9 Claims. (Cl. 313—299)

My invention relates to electronic tubes and pertains more particularly to new and improved means adapted for increasing the lives and operating efficiencies of electronic tubes.

In some electronic tubes, such as high-voltage regulators, the electrons travel in a beam or stream from the cathode to the anode. Often, due to the particular configurations of corona shields and other devices in the tubes, the beam is caused to converge on or concentrate at particular portions of the anode, resulting in localized hot spots. Such hot spots have the effect of shortening the life of a tube and decreasing the operating efficiency thereof. Additionally, in some tube structures such as high-voltage regulators electrical connection to the anode is made by means of a connector fitted on a conductive top cap suitably sealed in the tube envelope. To insure continued good electrical connection to the anode it is desirable to provide means for insuring a secure fitting of the connector to the top cap.

Accordingly, an object of my invention is to provide, in an electronic tube including means adapted for effecting an electron beam between a cathode and anode, new and improved means for increasing the life and operating efficiency of the tube.

Another object of my invention is to provide, in an electron tube including means adapted for effecting an electron beam between a cathode and anode, new and improved means for avoiding localized hot spots on the anode.

Another object of my invention is to provide, in an electronic tube including means adapted for effecting an electron beam between a cathode and anode, new and improved means for distributing the beam substantially equally over the surface of the anode.

Another object of my invention is to provide, in an electronic tube including means adapted for effecting an electron beam between a cathode and anode, new and improved means for distributing the beam in a controlled predetermined manner over the surface of the anode.

Still another object of my invention is to provide a new and improved electronic tube top-cap including means for insuring secure fitting of an electrical connector thereon.

Further objects and advantages of my invention will become apparent as the following description proceeds and the features of novelty which characterize my invention will be pointed out with particularity in the claims annexed to and forming part of this specification.

In carrying out the objects of my invention I provide a tube structure including an anode and a shielded cathode. The means for shielding the cathode is provided with an aperture for directing an electron beam from the cathode to the anode. Disposed in the path of the beam is means for spreading the beam in a predetermined manner thereby to effect control of the beam and a predetermined distribution of the beam on the surface of the anode. The anode is electrically connected to a

2

top-cap sealed to and extending through the tube envelope. The top-cap is formed to provide means for effecting a more secure fastening of a connector fitted on the cap.

5 For a better understanding of my invention reference may be had to the accompanying drawing in which:

Fig. 1 is an enlarged perspective view of an electronic tube with the envelope partially broken away to illustrate a preferred embodiment of my invention;

10 Fig. 2 is a fragmentary exploded perspective view illustrating the cathode shielding structure;

Fig. 3 is an enlarged fragmentary sectional view illustrating my invention in more detail and a manner in which the electron beam may be distributed over the

15 interior of the anode;

Fig. 4 is a sectional view taken along the line 4—4 in Fig. 3 and looking in the direction of the arrows;

Fig. 5 is an enlarged fragmentary detail view illustrating the connector-securing means provided on the top cap; and

Fig. 6 is a sectional view taken along the line 6—6 in Fig. 5 and looking in the direction of the arrows.

Referring to Fig. 1, there is shown an electronic tube of the high-voltage regulator type generally designated

25 1. The tube 1 includes an envelope 2 and a base 3, both of which are made of suitable insulative material. The envelope 2 includes a glass header or stem portion generally designated 4 which, in accordance with the customary practice, is formed separately of the upper or

30 bottle portion of the envelope and is suitable sealed at its periphery to the open end of the bottle thereby to complete the envelope. The stem 4 is formed to include a plurality of circularly arrayed pins or leads 5 which extend through and are suitably sealed in the glass portion of the stem. In a manner not shown, the lower ends of the leads 5 extend into and are suitably electrically connected to prongs 6 mounted in the base 3 in an array corresponding to that of the leads 5. The base 3 additionally includes a central bayonet plug for facilitating proper orientation and insertion of the tube in a tube socket.

35 Supported atop the stem 4 is a cathode and grid mount structure generally designated 7. As better seen in Figs. 2 and 3 the mount 7 includes a rectangular box-like structure 8 which shall hereinafter be referred to simply as the box 8. The box 8 comprises a member 11 formed of a conductive material and bent to provide the bottom and two ends of the box 8. The two sides of the box 8 comprise substantially rectangular plates 12 of mica or some other similarly insulative material. The end portions of the member 11 comprising the box ends are each fabricated at the side edges thereof with laterally extending tabs 13. The tabs 13 extend through suitable apertures in the plates 12 for holding the box structure intact and for being welded to stem leads 5 disposed at diagonal corners of the box 8 in the manner shown in Fig. 2. Thus the box 8 is suitably supported on the stem. Additionally, for a purpose which will be described in detail hereinafter the member 11 is electrically connected to the leads to which the tabs 13 are welded.

grid rods 17 provides support for a similar second grid designated 19. In a manner not shown an outer end of one of the inner pair of grid rods 16 is welded to an appropriate one of the stem leads 5 and one of the grid rods 17 is similarly welded to another one of the stem leads 5, thereby to provide for electrical connection to the grids.

The cathode sleeve 14 is provided with an elongated tab 20 which extends and is electrically connected to one of the stem leads 5, thereby to provide for electrical connection to the cathode.

Provided for fitting over the box 8, in the manner shown in Figs. 1 and 3, is a shield 22 formed of any suitable conductive shielding material. The shield 22 is cap-like in construction and includes a downwardly extending skirt portion 23. As seen in Fig. 1, the skirt portion 23 of the shield 22 is formed to include pendent tabs 24. The tabs 24 are disposed diametrically opposite and are secured, as by welding, to the two leads 5 to which the tabs 13 of the member 11 are welded, thereby to provide support and electrical connection for the shield 22 over the box 8 and with the skirt portion 23 thereof extending downward beyond the bottom of the box. The top or end portion of the shield 22 is provided with an aperture 25. Thus, except for the area defined by the aperture 25, the cathode 14 is completely shielded by the cap-like shield 22 and the metal member 11. Accordingly, when the cathode 14 is rendered emissive, as by energization of the filament contained therein, and suitable accelerating potentials are applied to the second grid 19 and the anode 27, electrons are caused to emanate from the cathode and grid mount 7 comprising the box 8 and the shield 22 in a beam or stream, indicated by the dash lines designated 26 in Fig. 3.

Provided for receiving the beam of electrons is a tubular or cylindrical anode 27. The anode 27 is opened at the lower end for receiving the electron beam and is closed at the upper end. Additionally, the upper end is suitably secured, as by welding, to a cylindrical top-cap 29. The top-cap 29 is sealed in the top of the envelope 2 and thereby the anode 27 is supported in the envelope with the mouth or open end thereof spaced above the shielded cathode. The cylindrical top-cap 29 is provided with a plurality of apertures 28 to reduce heat conduction from the anode 27 to the glass seal between the envelope 2 and the top-cap 29, thus preventing excessive thermal strain in the glass. Additionally, the top-cap 29 is formed to include an annular depression or groove 30, the purpose for which shall be described in detail hereinafter.

Now with particular reference to Figs. 1 and 3, it will be seen that if the apertures 25 in the shield 22 were alone relied upon for directing the electron beam 26 into the cylindrical anode 27 it would have a focusing effect on the beam. Such a focusing effect on the beam would cause the beam to converge on or be concentrated at a particular portion of the anode 27, such as the central portion of the top or end of the anode 27 indicated by 32. It will be understood that such concentration of the beam 26 would have the effect of causing a localized hot spot in the anode at 32 which would be undesirable from the standpoints of tube life and operating efficiency. Thus, it is desirable to provide means for distributing the beam 26 and, therefore, the effect thereof over the internal portion or surface of the anode 27, thereby to avoid any localized hot spots. To accomplish this I have formed the shield or cap 22 to include a member 31 in the aperture 25. The member 31 is formed to include radially extending portions which are each approximately .020" in width. The member 31 may be formed integral with the cap 22 and planar with respect to the bottom portion of the cap in the manner shown in Figs. 1 and 3 or may alternatively comprise wires, pieces of strip material or any similar elements suitably secured to the

5 cap so as to extend in a crisscross manner over the aperture 25.

The member 31 is disposed in the path of the beam 26 and is effective for substantially spreading or diverging the beam in the manner illustrated in Fig. 3. That is, the member 31 is effective for so spreading the beam 26 as to cause the electrons comprising the beam to strike the internal surface of the anode 27 in a pattern substantially like that shown in dot and dash lines in Figs. 3 and 4 and designated 33. It will be seen that by varying the width, height and configuration of the extending portions of the member 31 the member 31 may be rendered effective for distributing the beam 26 in a controlled predetermined manner over the inner surface of the anode 27 whereby localized hot spots and the deleterious effects thereof may be avoided.

As pointed out above, the member 31 need not be formed integral with the shield 22 but could be formed as a separate member and suitably secured in place in the path of the beam 26. It is to be further understood that while I have shown the member 31 as comprising four portions extending radially at 90° intervals, my invention is not limited to this particular arrangement of beam spreading means. The member disposed in the path of the beam 26 could comprise any number of portions extending at various desired angles and could be of any desired configuration. The member 31 could be shaped to provide any desired pattern configuration thereby to provide any desired predetermined beam distribution in the anode 27.

It will be seen still further that while I have shown my invention adapted for distributing an electron beam in a cylindrical anode 27, my invention is not limited to use with cylindrical anodes. It is equally applicable to tube structures including flat or disk-like anodes. Additionally, my invention is not limited to the particular cathode shielding arrangement shown and described. In practicing my invention it is sufficient that the cathode be shielded and an aperture be provided for directing an electron beam or stream toward an anode.

As seen in Figs. 1, 5 and 6, and as pointed out above, I have formed the top-cap 29 to include means for securely fitting thereon a connector 34 adapted for having a lead line 35 electrically connected thereto. The top-cap 29, as shown, is formed to include a reduced cylindrical intermediate portion which as shown may comprise the peripheral depression or groove 30. Thus the bottom of the groove is substantially transversely elongated and straight and the connector 34, which may comprise a plurality of turns of a resilient wire, when fitted on the cap will become seated in the groove 30 whereby the connector 34 will be securely fitted on the cap 29 and all of the turns of the connector will make satisfactory contact with the top-cap until the end portions 36 of the connector are compressed for releasing it from the cap. It will be seen that by the provision of the groove 30 unintended removal of the connector 34 from the cap 29 and unsatisfactory electrical connections are avoided.

While I have shown and described specific embodiments of my invention, I do not desire my invention to be limited to the particular forms shown and described, and I intend by the appended claims to cover all modifications within the spirit and scope of my invention.

65 What I claim as new and desire to secure by Letters Patent of the United States is:

1. In an electronic tube, an anode, a cathode, means interposed between said anode and said cathode and adapted for directing a beam of electrons from said cathode toward said anode, and crisscross elements disposed in the path of said beam in spaced relation to said anode and cathode for spreading said beam and thereby distributing the effect thereof on said anode.

70 2. In an electronic tube, an anode, a cathode, a shield interposed between said anode and said cathode and in-

cluding an aperture adapted for directing an electron beam toward said anode, and a member including a plurality of cross portions disposed in said aperture for spreading said beam and thereby distributing the effect of said beam on said anode.

3. In an electronic tube, an anode, a cathode, a shield interposed between said anode and cathode, said shield comprising a cap-like element fitted in spaced relation over said cathode and having an aperture therein for directing an electron beam toward said anode, said element carrying means disposed in the path of said beam for spreading said beam thereby to distribute the effect of said beam on said anode.

4. In an electronic tube, an anode, a cathode, a shield interposed between said anode and cathode, said shield comprising a cap-like element having an aperture therein for directing an electron beam toward said anode, said element including a plurality of crossing portions disposed in said aperture thereof for substantially spreading said beam and thereby distributing the effect of said beam on said anode.

5. In an electronic tube, a tubular anode, a cathode disposed adjacent an open end of said anode, a shield interposed between said anode and said cathode and including means adapted for directing an electron beam into said anode, and means disposed in the path of said beam effective for substantially spreading said beam thereby to distribute the effect of said beam over the internal surface of said anode.

6. In an electronic tube, a tubular anode, a tubular cathode extending transverse the longitudinal axis of said anode adjacent an open end of said anode, a shield interposed between said anode and cathode, said shield comprising a cap-like element having an aperture therein for directing an electron beam into said anode, said element including means disposed in said aperture effective for substantially spreading said beam thereby to distribute the effect of said beam on the internal surface of said anode.

7. In an electronic discharge device, an anode, a cathode, a box-like structure containing said cathode and being open on one side, a shielding element including a portion interposed between said anode and the open side of said box-like structure, said portion including an aperture adapted for directing an electron beam toward said

anode, and a plurality of elongated elements carried by said shielding element and crossing each other over said aperture effective for spreading said beam and thereby distributing the effect of said beam on said anode.

5 8. In an electric discharge device, a tubular anode including a cylindrical inner surface, a box-like structure including oppositely disposed insulative walls and an open side facing an open end of said anode, a cathode mounted between said insulative walls of said box-like structure, 10 a cathode-shielding element including a portion interposed between said anode and the open side of said box-like structure, said portion including an aperture for directing an electron beam into said anode, and crisscross elements disposed in the path of said beam effective for substantially spreading said beam and directing the electrons comprising said beam to a substantial area of said cylindrical inner surface of said anode.

9. In an electric discharge device, a cylindrical anode, 20 a box-like structure having an open side facing an open end of said anode, a cathode and control electrode mounted in said box-like structure, and a cap-like cathode shield fitted over said box-like structure in spaced relation thereto, said shield including a skirt portion extending beyond the sides of said box-like structure and a 25 bottom portion interposed between said anode and the open side of said box-like structure, said bottom portion including an aperture for directing an electron beam longitudinally into said anode, said bottom portion further including a plurality of elongated portions extending 30 in the same plane thereas and crossing each other at right angles in said aperture for substantially spreading said beam and distributing the electrons comprising said beam in a predetermined manner over the internal surface of said anode.
